PAUL KAMINSKI, OF BERLIN-PANKOW, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

APPARATUS FOR THE REMOTE ADJUSTMENT OF THE TRAVERSE OF GUNS, SEARCH-LIGHTS, OR THE LIKE WITH MOVABLE PLATFORM TOWARD A MOVABLE TARGET.

Application filed February 9, 1923. Serial No. 618,169.

To all whom it may concern:

Be it known that I, PAUL KAMINSKI, a citizen of the German Empire, residing at Berlin-Pankow, Germany, have invented 5 certain new and useful improvements in apparatus for the remote adjustment of the traverse of guns, searchlights, or the like with movable platform toward a movable target, of which the following is a specification.

10 The invention relates to improvements in apparatus which enables remote control apparatus, such as is for instance used on battleships for pointing guns, searchlights and 15 the like, to maintain the correct horizontal position towards a certain target even when the gun telescope has temporarily lost sight of the target owing to smoke. The apparatus is also intended to ascertain the horizontal 20 displacement of the point of impact necessary for firing and caused by the shifting of the positions by both ships.

The displacement of the point of impact for the travel of the own ship corresponds 25 with the formula

$$T_1 = f \cdot t \cdot \sin \alpha$$

in which represents: f the travel of the own ship in metres per second, t the time of 30 flight of the projectile and α the angle between the axis of the gun and the amidship axis.

The displacement of the point of impact for the travel of the enemy corresponds 35 with the formula

$$T_2 = g \cdot t \cdot \sin \beta$$

in which represents: g the travel of the enemy in metres per second, t again the time 40 of flight of the projectile and β the angle which the direction of descent of the projectile forms in the horizontal plane with the amidship axis.

Both formulæ represent two components 45 from which the total displacement of the point of impact may be construed as resultant, or into which the total displacement, if it be measured otherwise, may be analyzed.

For instance the total displacement may also be found by the formula:

$$T = \omega \cdot t = F (T_1, T_2)$$

in which represents: t again the time of flight and ω the angular speed with which the direction changes in which the enemy 55 appears. This latter value ω can suitably be ascertained by measuring the speed with which the gun telescope observing the enemy is turned.

In the accompanying drawings Fig. 1 60 shows a perspective view of the improved apparatus and Fig. 2 a modification of a detail.

Similar parts are indicated by the same numerals and letters of reference in both 65 figures of the drawings.

Referring to Fig. 1 of the drawings G indicates the electric transmitting device of the remote control plant connected with the telescope O , g_1 and g_2 being for instance a 70 rough and a fine system, which by the diagrammatically shown conductors 1 and 2 of, for instance, a three-wire alternating current system, are connected with the guns and the receivers e_1 and e_2 of a special receiving 75 station E , which may for instance be situated in the ship's electrical central station.

The pointers z_1 and z_2 controlled from a distance are in the known manner turned to follow counter pointers z_3 and z_4 by means 80 of a crank k_1 through the agency of a counter gearing planet wheel p_1 and shaft 3. The pointers z_3 and z_4 turn by spur wheels and intermediate members t_1 , t_2 the control transmitters g_3 and g_4 . These control members g_3 and g_4 are connected by diagrammatically shown conductors 4 and 5 with the control receivers e_3 and e_4 at the transmitting device G . The pointers z_5 and z_6 of the control receiver co-operate also with 90 counter pointers z_7 , z_8 , which are directly driven by the transmitters g_1 , g_2 by way of intermediate members t_3 , t_4 , similar to the device E . The shaft 3 which may be rotated by the crank k_1 , rotates furthermore 95 by a counter gearing 6 the frame b_1 of a

sine link of known construction. The block s_1 of this link is moved in known manner by rotating the crank k_2 , shaft 7, counter gearing 8, 9 and spindle 10. The shaft 7 carries a pointer z_9 by means of which the adjustment of the crank k_2 may be read off upon a dial A_1 , divided in accordance with the time of flight or the distance of the target, which latter contains the time of flight as a function. The link block s_1 moves the link h_1 parallel to the beam 11, which is constructed as a rack. This beam 11 rotates through the spur wheel 12 the frame b_2 of a second sine link, the block s_2 of which is moved by the crank k_3 through the agency of the shaft 13, transmission gearing 14, 15 and spindle 16. The shaft 13 carries a pointer z_{10} , which indicates the adjustment of the crank k_3 on the dial A_2 graduated in correspondence with "own travel in metres per second". The block s_2 in its turn moves the link h_2 parallel to its beam 17 constructed as a rack, which through an intermediate gearing 18, 19 drives the shaft 20. The shaft 20 turns through a transmission gearing 21 the pointer z_{11} which passes over a dial A_3 graduated in correspondence with the "horizontal correction for own travel". The shaft 20 also causes through the gearing 22 the shifting of friction roller r_1 upon the screw spindle 23. The friction roller r_1 takes up the motion of friction disc f_1 driven by a motor M through a transmission gearing 24 and shaft 25 and transmits it to a second friction disc f_2 , which through the agency of a gearing 26, 27 drives a planet wheel p_2 . This planet wheel p_2 is connected through the bevel wheel 28 with the planet wheel p_1 fixed upon the shaft 3. The shaft 25 driven by the motor M drives furthermore through a friction disc f_3 and the friction roller r_2 movable upon the spindle 29 by the crank k_4 , the friction disc f_4 . This disc rotates through, intermediate gearings 30, 31, a reversing drive W of conventional construction the bevel 32 and therethrough the planet wheel p_3 upon the shaft 33. Upon the planet wheel p_3 also acts the gyroscope compass K through a bevel gearing 34. The shaft 33 is connected with the planet wheel p_2 through the bevel wheel 35. The spindle 29 turned by the handle k_4 turns furthermore through the agency of an intermediate gearing 36 the shaft 37 upon which is fixed a cam C_1 . The contour of this cam depends upon the approximately quadratically varying ratio of transmission between the discs f_3 and f_4 , which through the shape of the cam C_1 is to be converted into a uniform motion. The cam C_1 moves the block s_3 guided in the slot of the stationary link h_3 . This block s_3 is also adapted to slide in the slot of a link h_4 , which is rotatable around the axis of the

tubular shaft 38 upon which it is fixed. The angular motion of this link h_4 is transmitted to the planet wheel p_4 upon the shaft 42 through the intermediate gearing 39, 40 and the bevel wheel 41, the said planet wheel p_4 being on the other hand connected through bevel wheel 43 with the shaft 7 adapted to be rotated by the crank k_2 . The shaft 42 carries at its free end a cam C_2 , which is shaped in correspondence with the curve, representing the time of flight as a function of the distance. Against the periphery of this cam C_2 is pressed by a spring (not shown) the link block s_4 guided in the slot of link h_4 previously mentioned, block s_4 engaging with its free end the link h_5 . The link h_5 can move only in the direction of its rack bar 44. This rack gears with a pinion 45, the shaft 46 of which moves the pointer z_{12} over the dial A_4 graduated according to "lateral correction for enemy's travel".

Such a mechanical gearing for adjusting an element, like the pointer z_{12} , in accordance with two different, variable values, as represented by the cams C_1 , C_2 may, independently of the other here described peculiarities of the construction illustrated, be generally utilized for apparatus where pointers are to be adjusted or other parts to be directly controlled, such as guns, search-lights, etc.

The transmitting station G of the control telescope O and the receiving station E are assumed to be also connected by an optic or acoustic order transmitting installation of any conventional form not illustrated here and which operates independently of the system described and which may consist for instance of a semaphore, a telegraph, a telephone or a speaking tube.

The apparatus operates as follows:

The operator at E adjusts the distance of the target (or time of flight) by means of the crank k_2 upon the dial A_1 and the own ships travel by means of the handle k_3 upon the dial A_2 , in accordance with the orders received from the order station G by means of the separate order transmitting installation, mentioned just before. He starts the motor M and throws in the reversing gear corresponding with the instructions received from the observer at the gun telescope. With the target location, operations by the telescope the transmitters g_1 and g_2 are actuated and thereby the receiver pointers z_1 and z_2 are adjusted. For the first target finding operations (as well as when changing the target) the operator at E causes the counter pointers z_3 and z_4 to coincide with the pointers z_1 and z_2 by turning the handle k_1 . Herby the pointers z_5 and z_6 at the transmitting station G are caused to coincide simultaneously with the pointers z_7 and z_8 carried along by the transmitters g_1 and g_2 .

g. After the pointers have been made to coincide the crank k_1 is released and mechanically locked in position in any suitable manner (not shown). By turning the crank 5 k_1 also the frame b_1 is simultaneously turned in correspondence with the side position (angle α) by the agency of the intermediate gearing 6, and as the time of flight is adjusted upon the dial A_1 , the rack 11 is moved 10 automatically by the amount time of flight multiplied by sine α . The frame b_2 is moved by the same amount. As on the dial A_2 , the own travel has been adjusted, the rack 17 and the gearing operated thereby (up to 15 shaft 23) is moved in correspondence with the formula:

$$\text{time of flight } x \text{ own travel } x \text{ sine } \alpha.$$

This motion represents the necessary lateral 20 correction for own travel, which now can be read off on the dial A_3 .

It may now first be assumed that the enemy is stationary, the friction roller r_2 is in zero position (i. e. in contact with the 25 center of disk f_3) and the own ship maintains her exact course, which means that the gyroscope compass K remains stationary. By rotating the shaft 23, as previously mentioned, the friction roller r_1 has 30 been shifted radially on disk f_1 in correspondence with the movements of the own ship and the distance of the target and the motor now turns in correspondence with these adjustments through gear 24, 25, discs 35 f_1, f_2 and bevel gears 26, 27 the planet wheel p_2 . As the bevel wheel 35 remains stationary under the above assumptions, p_2 , in 40 rolling off on wheel 35 turns through the agency of the bevel wheel 28 and the planet wheel p_1 the shaft 3 and thereby the counter pointers z_3 and z_4 travel automatically in correspondence with the variation in the target-bearing. The pointers z_1 and z_2 , 45 remotely controlled by the telescope, holding the target, remain therefore without special instructions for setting at the receiving station E in coincidence with the pointers z_3 and z_4 . As in the zero position of the friction roller r_2 the two links h_4 and h_5 are 50 parallel, the rotation of the cam C_2 during the adjustment of the distance of the target (or time of flight) by means of the handle k_2 by the agency of the shaft 7, bevel wheel 43, planet wheel p_4 and shaft 42 has caused 55 only a displacement of the link block s_1 , in the slot of link h_5 but no motion of this link and therefore no adjustment of the pointer z_{12} . Corresponding with the change of the target and the alteration of the lateral position resulting therefrom the position of the pointer z_{11} and the friction roller r_1 is automatically changed by the shaft 3 through the agency of the gear 6 and the frame b_1 .

60 If it is now assumed that the own ship

turns, the bearings of the target, that means the lateral position, will also change for each degree through which the ship turns. The shifting of the pointers z_3 and z_4 as well as of the frame b_1 depending upon this, 70 is in this case caused automatically by the gyroscope compass K through the bevel gear 34, planet wheel p_3 , shaft 33, bevel wheel 35, planet wheel p_2 , bevel wheel 28, planet wheel p_1 and shaft 3. The unintended small 75 deviation of the ship from her course owing to careless steering are hereby also corrected at all times.

Finally it may be assumed that the course of the own ship does not vary and the compass K remains stationary and the enemy travels a parallel course at equal speed in a running fight. As hereby no deviation of the bearing and consequently no change in the lateral position takes place, the pointers 80 z_3 and z_4 should remain stationary, as the pointers z_1 and z_2 do not move. The pointers z_3 and z_4 are however moved, according to the extent of adjustment of friction roller r_1 through the motor M by means the 85 planet wheel p_2 . To counteract this movement the friction roller r_2 is adjusted from zero position by the crankhandle k_4 until the pointers z_3 and z_4 remain stationary in coincidence with the pointers z_1 and z_2 , that 90 means the attendance at the station E subsequent to the first adjustment due to the searching for the target, by means of the crank k_1 is confined to the operator at the station E maintaining his counter pointers 95 z_3 and z_4 in coincidence with the remotely controlled pointers z_1 and z_2 . This happens when the motion of the shaft 25, driven by the motor M and transmitted by the discs 100 f_3 and f_4 , gear 30 and 31, reversing gear W, 105 bevel wheel 32, planet wheel p_3 , shaft 33 and wheel 35 to the planet wheel p_2 , is equal to the motion transmitted by the gear 27. The position of the friction roller r_2 is therefore 110 a measure for the deviation of the target caused by the run of the enemy. Its radial adjustment is transmitted through shaft 29 over gearing 36, 37 to cam C_1 . Hereby the block s_3 is raised, which swings the link h_1 around the axis of the tubular shaft 38 and thereby also moves the link h_5 by means of the block s_4 adjusted in accordance with the 115 time of flight. In this manner the pointer z_{12} is moved over the dial A_4 by a value corresponding with the lateral correction for the run of the enemy. In the example selected, equal run and parallel course in a running fight, the indication on the dial A_4 will be the same as that on dial A_3 . The clutch of the reversing gear will stand on 120 "minus" and the ballistic lateral correction therefore follows correctly as "zero".

If both ships move in opposite direction at equal speed for instance in a circular 125 fight, the reversing gear is thrown over on 130

"plus" and the wheel 32 runs at the same speed in the opposite direction. The transmission to the planet wheel p_3 is however in the circular fight now so changed by the 5 gyroscope compass K through the agency of the gearing 34, that the planet wheel p_3 and thereby the bevel wheel 35 have again the same speed as the gearing 24, that means the pointers remain stationary. The 10 ballistic lateral correction is now a function of the travels of both ships.

The pointer z_1 is at first turned into the position corresponding to the direction in which the enemy appears and then it is 15 moved with the same angular velocity as the enemy apparently moves. The pointer z_3 is at first turned into the opposite position to the pointer z_1 by turning the crank k_1 (the crank k_1 being thereafter mechanically locked). Therefore the relative position of these two pointers z_1 , z_3 is, after a 20 short time, a measure of the value ω in the above formulæ: Since from the intermediate gear 27 the value T_1 of the first formula 25 is transferred to the planet wheel p_2 , it follows that at each instance the position of the friction roller r_2 and therefore of the link h_4 always corresponds with the value T_2/t . As the block s_4 , adjusted according 30 to the time of flight, multiplies this value with t , it follows that the position of the pointer z_{12} must at all speeds and courses of the enemy supply the corresponding 35 lateral correction.

If the operator at the station E has adjusted the pointers z_3 and z_4 in correspondence with the motion of the pointers z_1 and z_2 and the guiding telescope at station G loses sight of the target for instance owing 0 to smoke, the observer at the telescope after having given appropriate orders over a separate order transmission system (for instance: do not follow.) without making special 5 adjustments may turn the telescope in such a manner, that he turns his pointers z_7 and z_8 to follow the pointers z_5 and z_6 , which rotate as before. When the smoke abates the observer will then still have the former target covered by his telescope, even 10 if the course has been changed or the ship has lurched unintentionally.

Fig. 2 illustrates a slightly modified construction, which in its essential features corresponds with Fig. 1, with the exception that the friction gearing has been somewhat modified. Equal or similar parts have been indicated by the same reference numerals or letters as in Fig. 1. The essential difference as compared with the construction illustrated in Fig. 1 is, that the motor M drives only a simple pair of friction discs f_5 , f_6 through the agency of the gearing 24 and shaft 25.

This combination of the friction gears requires also a different disposal of the re-

versing gear, as the sum or difference of the components of motion of both ships must already be contained in the position of the friction roller r_3 . In the modified apparatus shown in this figure the shaft 20 acts 70 therefore through the intermediate gear 47 upon a planet wheel p_5 , which by means of a spindle 48 adjusts the friction roller r_3 corresponding with the motion of the own ship. The crank k_4 acts upon gearing 36 75 by way of the shaft 29 and hence as described before. From the shaft 29 the planet wheel p_5 is simultaneously rotated through the intermediate gearing 49, 50, the reversing gear W and the intermediate 80 gearing 51, so that hereby the friction roller r_3 is additionally adjusted corresponding with the motion of the enemy. The adjustment of the friction roller r_3 changes the ratio of transmission between the friction 85 disc f_5 , driven by the motor M, as already described and the disc f_6 . This disc transmits its motion as already described, by way of gear 30, 31, 32, planet wheel p_3 , shaft 33, bevel wheel 35 and planet wheel p_1 to 90 the shaft 3, which causes the counter pointers to follow.

The combination of the two components of the run of both ships may, aside from the two manners described, also be effected 95 in any other suitable manner, for instance by a bevel gearing.

The invention is furthermore not confined to the described principle of the pointers which follow each other, but may equally 100 well be employed for direct remote control. For this purpose the handle k_4 is substituted by a driving mechanism, such as a small motor, which in known manner is connected by contact devices with the receiver 105 systems e_1 and e_2 and which shifts the friction roller r_2 until following the turning of the linkwork driven by the friction disc f_4 , these contacts are opened again. The central transmitting station C is then preferably 110 fitted with a switch, by means of which in the event the target is obscured by smoke or the like, the apparatus otherwise connected with the transmitters g_1 and g_2 , is switched over to the reserve transmitters 115 g_3 and g_4 and with which it simultaneously interrupts the circuit of the motor, which replaces the crank k_4 .

It will be understood that I do not limit myself to the exact construction and arrangement of the parts shown and that these may be varied within the scope of the claims without departing from the spirit or sacrificing any of the advantages of the invention.

What I claim as my invention is:

1. Improved apparatus for the remote adjustment towards a movable target of the traverse of a gun, search light or the like having a movable platform, comprising in 130

combination a directing telescope for following the target, an electric system consisting of a transmitter and a receiver of the "follow the pointer" type and adapted to transmit the lateral angular movements of said telescope, a plurality of driving devices for turning the control pointer of the receiver of said system, a plurality of mechanical elements adapted to regulate the agencies of said driving devices with regard to the movement of the platform and of the target, and means for turning said driving devices simultaneously according to the actual positions of said elements.

15 2. Improved apparatus for the remote adjustment towards a movable target of the traverse of a gun, search light or the like having a movable platform, comprising in combination a directing telescope for following the target, an electric system consisting of a plurality of transmitters and receivers of the "follow the pointer" type for fine and coarse transmission of the lateral angular movements of said telescope, a plurality of driving devices for turning the control pointers of the receivers for fine and coarse adjustment of said system, a plurality of mechanical elements adapted to regulate the agencies of said driving devices with regard to the movement of the platform and of the target, and means for turning said driving devices simultaneously according to the actual positions of said elements.

30 3. Improved apparatus for the remote adjustment towards a movable target of the traverse of a gun, search light or the like having a movable platform, comprising in combination a directing telescope for following the target, an electric system consisting of a transmitter and a receiver of the "follow the pointer" type and adapted to transmit the lateral angular movements of said telescope, a driving device for turning the control pointer of the receiver of said system, a group of mechanical elements adapted to regulate the agency of said device in correspondence with the formula $T_1 = f \cdot t \cdot \sin \alpha$, a second driving device for turning independently the control pointer of said receiver, a second group of mechanical elements adapted to regulate the agency of said second driving device for the additional amount as to enable said control pointer to follow the pointer of said receiver.

35 4. Improved apparatus for the remote adjustment towards a movable target of the traverse of a gun, search light or the like having a movable platform, comprising in combination a directing telescope for following the target, an electric system consisting of a transmitter and a receiver of the "follow the pointer" type and adapted to transmit the lateral angular movements

of said telescope, a device, including friction gears, for turning the control pointer of said receiver, a motor for driving said friction gears, a group of mechanical elements adapted to vary the ratio of said friction gears in correspondence with the formula $T_1 = f \cdot t \cdot \sin \alpha$, a second device, including friction gears, driven by said motor for turning said control pointer of said receiver independently of said first device, a second group of mechanical elements adapted to regulate the action of said second device of friction gears to move said control pointer an additional amount so as to cause it to follow the pointer of said receiver.

40 5. In an apparatus of the kind described comprising a directing telescope for following the target, an electric system comprising a transmitter and receiver of the "follow the pointer" type for transmitting the lateral angular movements of said directing telescope, two devices, including friction gears, for turning independently of each other the control pointer of said receiver, two groups of mechanical elements for regulating independently of each other the agencies of said friction gear devices so as to enable the control pointer to follow the pointer of said receiver, and means for indicating the actuation of each of said devices.

45 6. In an apparatus of the kind described comprising in combination a directing telescope and an electric system of the "follow the pointer" type for transmitting the lateral angular movements of said telescope, means for turning the control pointer of said receiver, an electric controlling device comprising a transmitter and a receiver of the "follow the pointer" type and an element coupled to said device and adapted to move the pointer of the transmitter of said controlling system in correspondence with the turn of said first named control pointer.

50 7. In an apparatus of the kind described the combination of a directing telescope, an electric system consisting of a transmitter and a receiver adapted to transmit the lateral angular movements of said telescope, means for turning the control pointer of said receiver into opposition to the pointer of said receiver, and a compass connected to said means for regulating said means according to changes of the course of the ship on which the apparatus is carried.

55 8. In an apparatus for correcting the transmission of angular movements of a directing telescope, the combination of a plurality of sine link devices, a group of three mechanical elements connected to said sine link devices and adapted to transmit thereto the lateral telescope angle, the time of flight t and the velocity of the own ship f , and a measuring device connected to said sine link devices for indicating the total ad-

justment according to the own travel (formula $T_1=f.t. \sin \alpha$) effected by said sine link devices.

9. In an apparatus of the kind described
5 the combination of a directing telescope, an electric system consisting of a transmitter and a receiver of the "follow the pointer" type for transmitting the lateral angles of said telescope, a group of devices for turning the control pointer of said receiver, a plurality of elements for controlling the actuation of said devices to turn said counter pointer with a velocity according to the formula $T_1=f.t. \sin \alpha$, another group of devices for turning said control pointer of said receiver independently of said first devices an additional amount so as to enable said control pointer to follow the pointer of said receiver, an arrangement comprising
15 a plurality of cooperating slotted links, cams and blocks coupled to said second group of devices, means for transmitting the time of flight to said last-named arrangement, and a measuring device connected to aforesaid arrangement and adapted to indicate the component of the change of the point of impact due to the movement of the target ($T_2=g.t. \sin \alpha$) adjusted by aforesaid arrangement.
- 20 10. In an apparatus of the kind described the combination of a directing telescope, an electric system consisting of a transmitter and a receiver of the "follow the pointer" type for transmitting the lateral angular movements of said telescope, a group of devices for turning the control pointer of said receiver, means for adjusting said devices according to the lateral telescope angle α and to the velocity of the own ship, another group of devices for turning said control pointer independently of said first devices and to an additional amount so as to enable it to follow the pointer of said re-

ceiver, an arrangement comprising a plurality of cooperating slotted links, cams and blocks coupled to said second group of devices, and a mechanical element for controlling the adjusting movement of said means and the operation of said arrangement according to the time of flight. 45

11. In an apparatus of the type described an arrangement for mechanically constructing the product of two variable functions, comprising in combination a rotatable cam representing by its periphery the curve of one of the variable functions, a block adapted to slide on the periphery of said cam, a second cam representing by its periphery the curve of the other variable function, a second block adapted to slide on the periphery of said second cam, a link having a slot adapted to guide said blocks, an indicating device, and means for transmitting to said indicating device the change of position of said blocks. 50

12. In an apparatus of the type described an arrangement for mechanically constructing the product of two variable functions and of a proportional variable value, comprising in combination a rotatable cam, representing by its periphery the curve of one of said functions, a block adapted to slide on the periphery of said cam, another rotatable cam representing by its periphery the curve of the second of said functions, a second block adapted to slide on the periphery of said second cam, a link having a slot adapted to guide said blocks, means for moving said link according to the proportional variable value, an indicating device, and means for transmitting to said indicating device the change of position of said blocks and of said link. 70

In testimony whereof I affix my signature.

PAUL KAMINSKI.
